UNITED STATES PATENT OFFICE

WILLIAM I. DERRICK, OF DAVENPORT, IOWA, ASSIGNOR TO WESTCO-CHIPPEWA PUMP COMPANY, OF DAVENPORT, IOWA, A CORPORATION OF DELAWARE

PUMP

Original application filed August 18, 1927, Serial No. 213,812. Divided and this application filed January 12, 1928. Serial No. 246,178.

This invention relates to rotary pumps of the type in which suction is created at the inlet and pressure at the outlet of the pump by the impelling action of the vanes carried by the peripheral portion of a rotor and acting on fluids carried in an unobstructed channel extending along the peripheral portion of the rotor from the inlet to the outlet.

This application is a division of my co-pending application Serial No. 213,812 that was filed on August 18, 1927 and that is entitled Pumps.

The main objects of the present invention are to provide a rotary pump of the character above referred to that is capable of developing considerable pressure and that is simple in construction and may be manufactured at low cost.

Other objects and advantages of the present invention are to provide a pump of the character described in which the vanes are formed in the rotor intermediate the center and circumference thereof, and in which the casing engages and supports the rotor on each side of its peripheral edge in a close working fit to prevent objectionable distortion thereof during operation because of load imposed on the rotor by the fluid impelling pockets formed therein and from other causes.

An additional object of this invention is to provide a fluid channel on each side of the rotor that, in combination with the apertured portion of the rotor, serves to propel the liquid through the two channels and provides a channel section of substantially continuous curvilinear form which serves to reduce the frictional resistance to the movement of fluids through the pump.

A further object of the invention is to provide a pump in which the rotor may be formed of a relatively thin flat metal plate that is substantially relieved from all transverse strains produced by differences in the pressure of fluids in the opposing channels and that has its outer edge portion beyond the liquid propelling apertures of the pump formed to make a relatively close working fit with the pump casing.

With the above and other objects in view, the invention may be said to comprise the

pump as illustrated in the accompanying drawings hereinafter described and particularly set forth in the appended claims, together with such variations and modifications thereof as will be apparent to one skilled in the art to which the invention appertains. 55

Reference should be had to the accompanying drawings forming a part of this specification in which:

Figure 1 is a side elevation of a pump embodying the invention, a portion of the casing being broken away to show the rotor and the construction of the casing inlet and outlet. 60

Fig. 2 is a sectional elevation of the pump looking from the left toward the pump as positioned in Fig. 1, the lower portion of the view showing the casing and rotor in radial section on line 2-2 of Fig. 1. 65

As shown in Figs. 1 and 2, the casing is formed of sections 1 and 2 that are held in registered relation by bolts 4 that extend through the marginal flanges 3. The casing is provided with a peripheral inlet 5 and a peripheral outlet 6 which are relatively close together. A transverse shaft 7, which passes through packing glands 8 in the opposite walls of the casing, has a rotor 9 in the form of a flat disc secured thereto and arranged to make a close running fit with the casing along its entire peripheral edge portion. The rotor disc 9 is provided with an annular row of closely spaced openings 10 that extend transversely through the disc and form between them impeller vanes 11. 75 80 85

Each of the sections 1 and 2 of the casing is provided upon its inner side with a channel 12 and these channels extend around the circumference of the casing from the inlet to the outlet alongside the annular row of openings in the rotor 9. At the inlet and at the outlet, the channels 12 extend past the periphery of the rotor through cored out passageways to form the inlet and outlet passages. The rotor 9 has a continuous peripheral portion 13 outside the annular row of openings 10 and a continuous inner portion 14 within the annular row of openings. 90 95

The casing members 1 and 2 are formed to have flat faces inwardly and outwardly of 100

the channels 12, which lie in close proximity to the portions 13 and 14 of the rotor to prevent leakage of water, the central portions of the inner faces of sections 1 and 2 being slightly recessed to provide spaces 15 upon opposite sides of the rotor. This reduces frictional resistance on the side faces of the rotor. The portions of the inner faces of the sections 1 and 2 of the casing between the ends of the channels 12 and lying between the inlet and outlet make close working fit with opposite sides of the disc so that there can be no free flow of water from the outlet back to the inlet, the space between the ends 10 of the channels being sufficient to cover more than one complete opening in the disc at all times during operation. The channels 12 through which the water flows from the inlet to the outlet are preferably of gradually 15 decreasing cross sectional area from the inlet to the outlet to compensate for the increase in speed of movement of the stream of liquid flowing from the inlet to the outlet. It should also be noted that the frictional resistance to flow of water through the pump 20 casing is small due to the fact that a large proportion of the wall surface of the combined passageway is formed by the rotor.

Water entering through the inlet 5 divides 25 and passes into the channels 12 extending along opposite sides of the rotor. It is then impelled toward the outlet by the action of the vanes 11 when the rotor is turning. Since the casing has close working fit with opposite sides of the rotor between the inlet and outlet, the only water that can pass from the outlet to the inlet is that carried in the openings of the rotor so that the pressure at the outlet is not dissipated through objectionable flow of water from the outlet back to the inlet.

In the pump structure above described, the rotor is in the form of a substantially flat disc and the impeller vanes are formed by the annular row of apertures through the disc inwardly of its periphery. The outer rim portion of the rotor has a close working fit with the casing that guides the rim of the rotor and prevents distortion of the rotor due to loads imposed thereon. It will be apparent, therefore, that both the rotor and casing are of simple and compact design, that very little machining is required, that the required machining is inexpensive and that the cost of manufacture is low. A further advantage of the openings through the disc is that lateral thrusts on the rotor tending to shift the same toward one side or the other of the casing are eliminated.

Furthermore, by providing a channel in the casing wall which extends only from the inlet to the outlet, the flat inner face of the wall between the inlet and outlet which lies closely adjacent the face of the rotor serves 65 to prevent back flow from the outlet to the

inlet making it unnecessary to provide special means upon the interior of the casing for preventing the back flow.

It will furthermore be understood that the particular forms of apparatus shown and described, and the particular procedure set forth, are presented for purposes of explanation and illustration and that various modifications of said apparatus and procedure can be made without departing from my invention as defined in the appended claims.

What I claim is:

1. A rotary pump comprising a rotor in the form of a disc having an annular row of transverse apertures therethrough, and a casing provided with an inlet and an outlet and having walls making a close working fit with each lateral face of the disc inwardly and outwardly of said row of apertures and closely fitting the side wall of the rotor between the inlet and outlet, said casing having an unobstructed channel formed therein alongside the row of apertures in the rotor and extending from the inlet to the outlet on each side of the rotor.

2. A rotary pump comprising a rotor having an annular row of transverse apertures therein, and a casing provided with an inlet and an outlet and having walls closely overlying the face of the disc inwardly and outwardly of said row of apertures and between the inlet and outlet, the opposite walls of said casing having channels alongside said row of apertures which form unobstructed passages from the inlet to the outlet.

3. A rotary pump comprising a rotor in the form of a disc having transverse apertures closely spaced throughout its circumference, said apertures being elongated and extending inwardly from adjacent the circumference of the disc, a casing having a peripheral inlet and a peripheral outlet adjacent the inlet and having side walls closely overlying the opposite side faces of the apertured portion of the disc, each of said walls having a channel extending circumferentially alongside the apertured portion of the disc from the inlet to the outlet, each of said side walls lying closely adjacent the face of the disc on opposite sides of the channel and lying closely adjacent the apertured portion of the disc between the inlet and outlet, said inlet and outlet being spaced apart circumferentially a distance sufficient to permit the overlying side walls of the casing to cover a plurality of rotor apertures between the inlet and outlet.

4. A rotary pump comprising a rotor having apertures extending transversely therethrough and closely spaced throughout the circumference of the rotor, a casing formed of mated sections having an inlet and an outlet and a channel overlying each side of the apertured portion of the rotor, said channels extending circumferentially along each

face of the rotor from the inlet to the outlet, the side walls of said casing making a close working fit with the opposite faces of the apertured portion of the rotor between the inlet and outlet portions of said channels and the sides of the rim portion of said rotor and said casing engaging in a running fit throughout its periphery.

5. A rotary pump comprising a rotor having closely spaced elongated transverse apertures each extending inwardly from adjacent the periphery of the rotor and throughout the circumference thereof, the apertured portion of said rotor having side faces in planes perpendicular to the axis thereof, and a casing having flat side walls closely overlying the opposite side faces of the apertured portion of the rotor, said casing being provided with an inlet and an outlet and said side walls with channels extending circumferentially alongside the apertured portion of the rotor from the inlet to the outlet, said inlet and outlet being spaced circumferentially a sufficient distance to provide flat wall portions closely overlying a plurality of apertures.

In testimony whereof I affix my signature
WILLIAM I. DERRICK
